UNITED STATES PATENT OFFICE.

LOUIS CHARLES KRUMMEL, OF CLINTON, CONNECTICUT.

MECHANISM FOR FEEDING CAN-BODIES AND CAN ENDS TO A CAN-MAKING MACHINE.

1,091,468.

Specification of Letters Patent. Patented Mar. 24, 1914.

Application filed February 24, 1911. Serial No. 610,464.

To all whom it may concern:

Be it known that I, LOUIS C. KRUMMEL, a citizen of the United States, residing at Clinton, in the county of Middlesex, State of Connecticut, have invented certain new and useful Improvements in Mechanism for Feeding Can-Bodies and Can Ends to a Can-Making Machine, of which the following is a description, reference being had to the accompanying drawing and to the letters and figures of reference marked thereon.

The invention relates to new and useful improvements in mechanism for feeding can bodies or for feeding can ends to a can making machine, and more especially to a can making machine wherein the can end is connected to the can body by a rolled seam.

An object of the invention is to provide means independent of a continuously rotating carrier for feeding can bodies to operating members carried by and moving with the carrier, which means sustains the can body until engaged by the operating members.

25 A further object of the invention is to provide means for feeding in a similar manner, can ends, together with the can bodies and for sustaining the same until the can end is clamped to the can body.

30 A further object of the invention is to provide means of the above character with devices whereby the same may be readily adapted for can bodies of different sizes.

These and other objects will in part be obvious and will in part be hereinafter more fully described.

In the drawings which show by way of illustration, one embodiment of the invention; Figure 1 is a vertical sectional view 40 through a rotary double seaming machine, showing my invention applied thereto; Fig. 2 is a longitudinal sectional view of the same; Fig. 3 is a detail sectional view on the line 3, 3, of Fig. 1; Fig. 4 is a detail sectional view on the line 4, 4 of Fig. 1; Fig. 5 is a horizontal sectional view through the post for moving the can bodies and ends on the support; Fig. 6 is a sectional view on the line 6, 6, of Fig. 1; Fig. 7 is a plan view of 45 the can body support; Fig. 8 is a vertical section on line 8—8 of Fig. 7.

In carrying out my invention, I have provided a supporting base 1 from which rises standards 2, carrying an axle 3 on which 50 rotates a sleeve 4. The sleeve is rotated by means of a gear 5 which is connected with

a gear 6 on the main shaft. Mounted on the sleeve 4 is a bracket 7, which carries a plurality of bearings 8 in each of which is mounted a rotating chuck 9 carried by a 60 spindle 10 operated by a gear 11, which is connected to a gear 12 carried by a sleeve 13, which is operated by a gear 14 meshing with a gear 15 on the main shaft. As all the operating stations are identical, I shall only 65 describe one of them.

Coöperating with each rotating chuck, is a second rotatable member 16. Said rotatable member is formed with a head 17 adapted to fit the open end of the can body, and a 70 collar 18 is normally spring-pressed outwardly against said head by the springs 19. The rotatable member 16 is carried by a sliding member 20 which is moved in and out of the supporting bracket 21 carried by 75 the sleeve 4, by a cam 22 which is freely mounted on the bracket 21 and held from movement by a pin 23, which extends through one of the standards 2.

Extending through the spindle for the 80 chuck, is a rod 24 which carries a seating pad 25. The rod 24 is normally held seated within the chuck by a spring 26 (see Fig. 2.) The outer end of the rod 24 is formed with a hardened projection 27 which at times engages the cam 28, which is carried by the supporting frame of the machine, and this cam causes the seating pad to be moved from the chuck into engagement with the can end. Mounted also on the carrier and rotating therewith, are a plurality of seaming tools or rollers 29. These rollers are mounted on carriages 30 which are swung about their pivots by stationary cams 31 mounted on the rotating sleeve. 85

The cams 31 may be held from rotating by any suitable means such as an arm which extends outwardly and engages some fixed part of the machine. These cams as clearly shown in dotted lines, in Fig. 1, extend only 90 part way throughout the circumference of the supporting sleeve, and will operate therefore, to move the seaming rolls into and out of operative engagement with the can ends during each rotation of the carrier. Two 105 cams are provided, one operating the first curling roll, and the other the flattening roll.

The above described parts form no part of the present invention *per se*, but have 110 been described as a preferred mechanism for operating upon the can bodies and can

ends which are fed thereto by my improved feeding mechanism. The parts herein described are more fully shown, described and claimed in my copending application 5 #535,680, filed December 30th, 1909.

As a means for feeding can bodies to the operating members on the rotating carrier, I have provided a can body support which is stationary relative to the carrier. Said 10 can body support is mounted on suitable brackets 32, which are adjustably supported by rods 32^a. The upper rod 32^a is carried by vertical arms 32^b, which are secured to the end standards of the machine. The 15 lower rod 32^a is secured to laterally projecting arms 32^c, which are also attached to the end standards. The ends of the brackets 32 are split and are clamped by suitable nuts to the rods 32^a.

20 Attached to the brackets by suitable screws, are supporting plates 34. The can body chute, is formed by spaced side rails 33, which are riveted to the supporting plates 34. As herein shown, the spaced 25 guide rails 33 are deflected laterally at their lower ends so that the can bodies as they are leaving the guide rails, will move substantially in a radial direction relative to the carrier. It is obvious however, that the 30 guide rails of the chute may be straight throughout their entire length, or located in other positions, if desired. A plate 34^a is attached to the lower end of each set of the 35 guide rails 33 and projects laterally relative to the plate 34, and serves as a means for supporting the guiding rails 35 and 36 for the can bodies. The guide rail 35 is riveted to the plate, while the guide rail 36 is preferably pivoted to the supporting plate 34^a, 40 as will be hereinafter more fully described.

The guiding rails 33 which form one side of the chute, are also grooved as at 33^a (see Fig. 7) to form a guiding channel for the can end, so that the can ends may be fed to 45 the carrier in substantially the same way as the can body is. The guiding rails 35 (as shown in Fig. 8) are curved concentrically to the axis of the rotating carrier. It will be obvious however, that from certain 50 aspects of the invention, these supporting rails may not necessarily be curved concentrically to this axis, but may be otherwise shaped, or straight, the essential feature being a supporting means on which the can 55 bodies may be given a movement in the general direction of the movement of the carrier, before they are clamped by the chuck of the seaming mechanism. The can bodies and can ends will drop from the vertical 60 chute on to the guiding rails 35 along which they may be moved in a forward direction. The guiding rail 35 at the left hand end of the can body, (as shown in Fig. 3) is provided with an upwardly projecting supporting rib 37 on which the can body rests, and

a flange 38 which projects above the lower portion of the end of the can body to prevent the same from endwise movement on the rails. The rib 37 is so placed however, as to allow at a proper time, a movement of 70 the can body on the rib without the flange on the can body striking said rib. The upper rail 36 at the left hand end of the can body, is also provided with a rib 39, and a flange 40, which are similar in construction and operation respectively, to the rib 37 and flange 38 on the rail 35.

The supporting rail 35 at the right hand end of the can body (as shown in Fig. 3), is formed with a supporting rib 41 and a 80 flange 42, which projects upwardly above the lower portion of the end of the can body and also with a second flange 43, similar to the flange 42 but spaced therefrom, to form a channel 44 for the can ends. The upper rail 36 at the right hand end of the can body as viewed in Fig. 3, is formed with spaced flanges 45 and 46, which are similar in construction and operation, to the flanges 42 and 43. These flanges 45 and 46 form a channel 90 for the can ends. At the left side of the upper right hand rail 36, is a plate 47, which is formed with a retaining rib 47^a, similar to the rib 39 on the other rail 36. Each of the rails 36 is pivoted at 48 to its supporting plate 34^a. Also the plate 47 is pivoted in a similar manner. The guiding rails 36, and the plate 47 are normally spring-pressed downward, by springs 49. A pin 50 carried by the supporting plate 34^a and extending 100 through an enlarged opening in the plate 47 and the rail 46, limits the movements of both, under the influence of the springs 49 which bear thereon.

When the can body is passing between the rails 35 and 36, the left hand rail 36 and the plate 47 will be pressed against the can body. This forms a slight drag on the can body and holds it properly against the member moving the same against the support which will be hereinafter more fully described. The rail 36 at the right hand end will be spring-pressed against the can end, and serve in a similar manner to retard its movement on the rail 35. While I have shown these upper rails as spring-pressed, it is obvious that from certain aspects of the invention, it may be made stationary and I may depend solely upon the inclined position of the rails and the action of gravity to 110 properly hold the can body and can end against the member moving the same.

The can bodies passing down through the chute by gravity will drop on to the ribs 37 and 41 of the supporting rails 35. The can ends will also pass down through their guiding channels in the chute into the channel in the supporting rail 35 at the right of the can body as viewed in Fig. 3. In this position, the can body and can end will rest by 120

gravity against the lower end of the left hand guiding rails 33 as viewed in Fig. 8. As a means for moving the can body and can end along the stationary support, I have 5 provided the rotating carrier with a supporting ring 51 which is mounted on projecting studs 52, carried by the bracket 7. Said ring 51 is formed with a flange 53 and at each seaming station I have formed a 10 post 54 (see Fig. 1) which is clamped to a face on the flange 53, by a bolt 55^a, as herein shown.

The post 54 projects laterally and upwardly, and is formed with an enlarged head 15 55, at its upper end, which carries spaced ribs 56 (see Fig. 5). This post as the carrier rotates will engage the can bodies and can ends resting on the supporting rails 35, and will move the same along the rails at 20 the same speed of travel as the carrier. The spaced ribs 56 will hold the can body concentric with the can end as shown in Fig. 5, so that the can end is in proper position to be seated in the can body.

25 The flanges 38 and 40 on the guide rails 35 and 36, are cut away near the delivery ends of the rails, so as to allow the head 17 and the collar 18 to be moved inward between the rails 35 and 36 and the head 17 30 to be seated in the open end of the can body. The flanges 42 and 45 are also cut away as shown in Fig. 1, so as to allow the can body to be moved against the can end and the can end seated in the can body (see Fig. 4). 35 The flanges 43 and 46 are also cut away so as to allow the seating pad 25 to be moved against the can end and to seat the can end in the can body, as the can body is moved on to the can end by the movement of the head 40 17 through the action of the stationary 45 cam 22.

In the operation of my device the can body and can end resting on the supporting rails 35, are picked up by the enlarged head 45 on the post 54 and are rolled or slid along the supporting rails in unison with the travel of the carrier. The cam 22 moves the head 17 and collar 18 against the open end of the can body, and a continued movement through 50 the action of the cam 22 will move the can body longitudinally on the supporting rails, and carry the same into position to engage the can end. The seating pad 25 is moved up against the can end. A continued movement of the head 17 will cause the end to 55 enter the open end of the can body, and the collar 18 will compress the springs 19 and move back against the member 16. The co-operation of the seating pad 25 and the head 60 17, together with the collar 18, will cause the can end to be seated in the can body and the can body and can end to be clamped between these parts and moved along with the carrier.

65 As the carrier continues its movement, the

can body and can end clamped between the seating pad and the head 17, will be carried from between the rails 35 and 36. The head 17 and the seating pad 25 will now be moved longitudinally of the can body, carrying the can body and can end clamped between the same on to the rotating chuck 9, and after the can body is clamped between the head 17 and rotating chuck, the seating pad 25 will be released from pressing the can end through the action of the spring 26, and the can body and can end may be rotated together. The seaming rolls are moved into engagement with the rotating can-end first one roll and then the other contacting with the can end to form the usual double seam.

When it is desired to operate upon can bodies of different sizes, the supporting bracket 21 for the rotating head 17, is moved longitudinally of the sleeve 4, so as to properly space the rotating head from the rotating chuck. The seaming rollers are also properly positioned for operating upon the proper size cans. I prefer to form the 90 guiding rails and supporting plates in units wherein the rails are fixed on the plates for the different size cans, and the plate together with the rails are removed and another plate having the rails differently spaced is substituted therefor. It is obvious however, that the rails may be adjusted on the supporting plate if desired. The post 54 will also be properly adjusted relative to the center of rotation of the seaming station for the different size cans. Mounted on the head 55 of the post 54, is an arm 37 which is pivoted at 58 in a recess in the head 55. This arm projects laterally and is formed with a shoulder 59. A spring 60 holds the arm 37 in 95 position so that the shoulder 59 is in line with the rib 56, and will engage the outer end of the can body as shown in Fig. 5. The arm 37 is yielding so as not to interfere with the proper clamping of the can body and the 100 seaming of the same. For smaller size cans, the arm 37 is removed.

While I have shown my device as applied to a double seaming machine, it will be apparent from certain aspects of the invention, 115 the means for feeding the can bodies may be used independently of the means for feeding the can ends, as for example in feeding can bodies to a flanging machine, in which case the can bodies would be held on the stationary support until engaged by the 120 flanging tool.

It will also be obvious that a can end may be fed by my improved means at each end of the can body, as for example, in heading 125 cans.

Various other uses and adaptations of my device will be apparent to those skilled in the art to which my invention relates, and it will be understood that I do not wish to 130

limit myself either to the details of construction herein shown, or to the use of my mechanism in a double seaming machine except as defined in the claims.

5 Having thus particularly described my invention, what I claim as new and desire to secure by Letters Patent, is:—

- 10 1. A can-making machine including in combination, a carrier rotating continuously, operating members mounted on the carrier, means for feeding can bodies to said operating members including a feeding chute, a stationary support for the can bodies extending from said feeding chute in a direction concentric to the axis of the carrier on which the can bodies may rest and move, and means for moving the can bodies on the support in unison with the movement of the carrier.
- 20 2. A can making machine including in combination a carrier rotating continuously about a horizontal axis, operating members mounted on said carrier, means for feeding can bodies to said operating members including a feeding chute, a stationary support for the can bodies extending from said feeding chute in a direction concentric to the axis of the carrier on which the can bodies may rest and move, and means for moving the can bodies on the support in unison with the movement of the carrier.

- 35 3. A can making machine including in combination a continuously rotating carrier, means for clamping and supporting a can body and can end, said means being mounted on said carrier, means for feeding can bodies and can ends to said clamping means, including a stationary support located between the paths of travel of the 40 clamping means, means for moving the can body and can end on the support in unison with the movement of the carrier, and devices for causing the clamping means to engage the can end and can body while on said support.

- 45 4. A can making machine including in combination a carrier rotating about a horizontal axis, a seating member and clamping head mounted on said carrier, a chuck concentric with said seating head, means for feeding can bodies and can ends to the carrier including a stationary support for supporting the can end and can body between the paths of travel of the seating member and clamping head, means for engaging the can end and can body and moving the same in unison with the movement of the carrier, said means being disposed so as to hold the can body and can end in substantially axial alignment with the supporting head and seating member, and means for causing the supporting head and seating member to engage the can end and can body and seat the can end in the can body while on the can body and can end.
- 50 5. A can making machine including in combination a carrier rotating about a horizontal axis, a seating member and clamping head mounted on said carrier, a chuck concentric with said seating head, means for feeding can bodies and can ends to the carrier including a stationary support concentric with the carrier for supporting the can end and can body between the paths of travel of the seating member and clamping head, means for engaging the can end and can body and moving the same in unison with the movement of the carrier, said means being disposed so as to hold the can body and can end in substantially axial alignment with the supporting head and seating member, and means for causing the supporting head and seating member to engage the can end and can body and seat the can end in the can body while on the can body and can end.
- 55 6. A can making machine including in combination, a carrier rotating about a horizontal axis, a seating member and clamping head mounted on said carrier, a chuck concentric with said seating head, means for feeding can bodies and can ends to the carrier including a stationary support concentric with the carrier for supporting the can end and can body between the paths of travel of the seating member and clamping head, means for engaging the can end and can body and moving the same in unison with the movement of the carrier, said means being disposed so as to hold the can body and can end in substantially axial alignment with the supporting head and seating member, and means for causing the supporting head and seating member to engage the can end and can body and seat the can end in the can body while on the can body and can end.
- 60 7. A can making machine including in combination, a carrier rotating about a horizontal axis, means for attaching a can end to a can body mounted on said carrier, means for feeding can ends and can bodies to said attaching means including a stationary support substantially concentric with

65 said stationary support, and means for subsequently causing said chuck to be engaged by the can end.

5. A can making machine including in combination a carrier rotating about a horizontal axis, a seating member and clamping head mounted on said carrier, a chuck concentric with said seating head, means for feeding can bodies and can ends to the carrier including a stationary support concentric with the carrier for supporting the can end and can body between the paths of travel of the seating member and clamping head, means for engaging the can end and can body and moving the same in unison with the movement of the carrier, said means being disposed so as to hold the can body and can end in substantially axial alignment with the supporting head and seating member, and means for causing the supporting head and seating member to engage the can end and can body and seat the can end in the can body while on the can body and can end.

85 6. A can making machine including in combination, a carrier rotating about a horizontal axis, a seating member and clamping head mounted on said carrier, a chuck concentric with said seating head, means for feeding can bodies and can ends to the carrier including a stationary support concentric with the carrier for supporting the can end and can body between the paths of travel of the seating member and clamping head, means for engaging the can end and can body and moving the same in unison with the movement of the carrier, said means being disposed so as to hold the can body and can end in substantially axial alignment with the supporting head and seating member, and means for causing the supporting head and seating member to engage the can end and can body and seat the can end in the can body while on the can body and can end.

90 7. A can making machine including in combination, a carrier rotating about a horizontal axis, means for attaching a can end to a can body mounted on said carrier, means for feeding can ends and can bodies to said attaching means including a stationary support substantially concentric with

the axis of the carrier, a post mounted on the carrier and having a head for engaging the can body and can end for moving the same on said stationary support in unison with the movement of the carrier whereby the can end and can body may be engaged with the attaching means while on said stationary support.

8. A can making machine including in combination, a carrier rotating about a horizontal axis, means for attaching a can end to a can body mounted on said carrier, means for feeding can ends and can bodies to said attaching means including spaced supporting rails concentric with the axis of the carrier, a post mounted on the carrier and positioned to move between said rails, a head on said post for engaging the can body and can end for moving the same on the rails in unison with the movement of the carrier, whereby said can end and can body may be engaged by the attaching means while on said supporting rail.

9. A can making machine including in combination, a carrier rotating about a horizontal axis, means for attaching a can end to a can body mounted on said carrier, spaced supporting rails for the can body and can end concentric with the axis of the carrier, retaining rails spaced above the supporting rails, one of said retaining rails having a yielding member to engage and retard the movement of the can body, and means for moving the can body and can end on the rails in unison with the movement of the carrier.

10. A can making machine including in combination, a carrier rotating about a horizontal axis, means for attaching a can end to a can body mounted on said carrier, spaced supporting rails for the can body and can end concentric with the axis of the carrier, retaining rails spaced above the supporting rails, one of said retaining rails having a yielding member to engage and retard the movement of the can body, a post mounted on said carrier and positioned to move between the supporting rails, said post having a head for engaging the can body and can end, for moving the same on the rails in unison with the movement of the carrier.

11. A can making machine including in combination, a carrier rotating about a horizontal axis, a plurality of independently operated devices for attaching can ends to can bodies, said devices being spaced on the carrier to form independent operating stations, means for feeding can bodies and can ends to the operating stations on the carrier, including a stationary support concentric with the axis of the carrier, and means located adjacent each operating station for engaging a can body and can end, and mov-

ing the same on said stationary support, whereby the can end and can body may be engaged by the attaching devices during the travel of the carrier.

12. A can making machine including in combination, a carrier rotating about a horizontal axis, a plurality of devices mounted on the carrier for attaching a can end to a can body, said devices being spaced about said carrier to form a plurality of separate operating stations, means for feeding can bodies and can ends to said stations, including a stationary support for the can body and can end, said support being concentric to the axis of the carrier, a post located adjacent each operating station, a head carried by said post for engaging the can body and can end for moving the same on the support, said head being positioned to hold the can body and can end in substantially axial alignment with the center of the operating station, whereby the can end and can body may be engaged by the attaching devices during the travel of the carrier.

13. A can making machine including in combination, a carrier rotating about a horizontal axis, a seating member, a rotating chuck and a rotatable head mounted on said carrier in axial alignment, means for feeding can ends and can bodies to the carrier including supporting rails, having ribs for supporting the can body and flanges for guiding the can body on the ribs, one of said rails having a separate flange forming a channel for the can end, said flanges for the can body being cut away throughout a part of the extent of the rail to allow the can body to be moved endwise on to the can end, means for moving the rotating head into the can body while on the support for moving the same longitudinally on to said end, means for causing the seating member to engage said end whereby the can body and end will be clamped between the rotatable head and seating member, and means for moving the can end and can body on the rails in unison with the movement of the carrier and in axial alignment with the rotatable head and seating member.

14. A can making machine including in combination, a rotating carrier, a seating member, a rotatable head and a rotating chuck mounted in axial alignment on said carrier, means for feeding can ends and can bodies to said support including stationary supporting rails having supporting ribs and flanges for guiding the can body on said ribs, retaining rails spaced above said supporting rails and having similar ribs and flanges, additional flanges mounted on the supporting and retaining ribs at one end of the can body, and spaced to form guiding channels for a can end, the flanges for supporting the can body being cut away throughout a portion of the

- extent of the rails to allow the can body to be moved endwise on to the can end, means for moving the rotatable head into the can body and for moving the can body endwise on to the can end, means for moving the seating member against the can end for holding the same and for clamping the can body and can end against the rotatable head, and means for moving the can body and can end on the supporting rails in axial alinement with the rotatable head and seating member.
15. A can making machine including in combination, a rotating carrier, a seating member, a rotatable head and a rotating chuck mounted in axial alinement on said carrier, means for feeding can ends and can bodies to said support including stationary supporting rails having supporting ribs and flanges for guiding the can body on said ribs, retaining rails spaced above said supporting rails and having similar ribs and flanges, additional flanges mounted on the supporting and retaining ribs at one end of the can body and spaced to form guiding channels for a can end, the flanges for supporting the can body being cut away throughout a portion of the extent of the rails to allow the can body to be moved endwise on to the can end, means for moving the rotatable head into the can body and for moving the can body endwise on to the can end, means for moving the seating member against the can end for holding the same and for clamping the can body and can end against the rotatable head, one of said retaining rails being yieldingly pressed against the can body for retarding the movement of the same on said rails, and means for moving the can body and can end on the supporting rails in axial alinement with the rotatable head and seating member.

16. A can making machine including in combination a supporting bed, a carrier mounted on said bed to rotate about a horizontal axis, devices for attaching a can end to a can body mounted in said carrier, means for feeding can ends and can bodies to said attaching devices including spaced rails forming a feed chute for the bodies and ends, a standard extending upward from the bed and carrying said rails, a plate mounted on said rails, spaced supporting rails carried by said plate and being formed concentric with the axis of the carrier, the supporting rails at one side of said feed chute terminating at a point above the lower concentric supporting rails, whereby a space is formed between the same, a supporting post mounted on the carrier, said supporting post having a laterally projecting head adapted to pass between the rails of the feed chute and the lower concentric rails and engage the can body and can end and move the same on said concentric rails.

17. A can making machine including in combination, a carrier rotating about a horizontal axis, operating members mounted on the carrier, means for feeding can bodies to said operating members including a support for the can bodies on which the can bodies may move until engaged by the operating members, and means for moving the can bodies on the support, said means including a post movable with the carrier, and a yieldingly mounted arm, carried by the post and engaging the can body at a point at one side of said post.

In testimony whereof I affix my signature, in presence of two witnesses.

LOUIS CHARLES KRUMMEL.
